SAFETY CATCH FOR WRIST WATCH BANDS, BRACELETS, NECKLACES, AND OTHER JEWELRY

Emanuel M. Alkin, New York, N. Y., assignor
to Morays Watch Case Co., Inc., New York,
N. Y.

Application July 26, 1935, Serial No. 33,208

5 Claims. (Cl. 24—265)

This invention relates to new and useful improvements in a safety catch for wrist watch bands, bracelets, necklaces, and other jewelry.

The invention has for an object the construction of a safety catch as mentioned which is characterized by a central body and inner and outer catch leaves associated therewith in a novel manner.

More particularly, it is proposed that the inner catch leaf be pivotally mounted on the central body and extendible over the bar portions of a link of a chain for the wrist bracelet or other object, and associated with a means by which it is held closed on the central body.

Still further the invention contemplates the provision of a means for holding the outer catch leaf closed over the inner catch leaf so as to reinforce the holding thereof and insure against the accidental opening of the catch.

Another one of the objects of this invention relates to the specific means by which the inner catch leaf is latched to the central body.

In one form of the invention it is proposed to utilize a bolt element slidably arranged on the inner catch link and maintained frictionally in various adjusted positions by a novel construction, and adapted to cooperate with a portion of the central body to hold the inner catch leaf in its closed position.

Another object of the invention is the construction of a device as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a plan view of a safety catch constructed according to this invention and associated with a pair of links from the chain of a wrist bracelet or other piece of jewelry.

Fig. 2 is an edge elevational view of Fig. 1.

Fig. 3 is a perspective view of Fig. 2, the device being shown with the outer catch leaf opened.

Fig. 4 is a sectional view as though taken on the line 4—4 of Fig. 3, but showing the device with both catch leaves open.

Fig. 5 is a sectional view similar to Fig. 4 but illustrating the device with both catch leaves closed.

Fig. 6 is a perspective view of the inner catch leaf per se.

Fig. 7 is a perspective view of the central body per se.

Fig. 8 is a fragmentary sectional view taken on the line 8—8 of Fig. 4.

Fig. 9 is a view similar to Fig. 4 but illustrating a modified form of the device.

Fig. 10 is a perspective view of the inner catch leaf of the device shown in Fig. 9.

The safety catch, according to this invention, 5 comprises a central body 10, links 11 from the chain of a bracelet or other piece of jewelry, and inner and outer catch leaves 12 and 13, respectively, associated with the central body and the links in a specific relation.

More particularly, the inner catch leaf 12, at the inner end thereof, has a trunnion 14 which engages a pair of lugs 15 on the sides of the central body 10. The inner catch link 12 is adapted to be extended over a bar 16 of one of the links 11. 10 The central body 10 has side walls 10^a which are slightly spaced from the lugs 15. It is in these spaces, indicated by reference numerals 17, in which the transverse bar 16 of the link is disposed. The catch leaf is extended over the bar 16 when closed, and is disposed in between the side walls 10^a of the central body.

The means for latching the inner catch leaf in its closed position comprises a bolt element 18 slidably mounted on the inner catch leaf and 25 adapted to coact with a portion of the central body. This portion consists of a lip 19 extended from an end wall 20 of the central body. The bolt element 18 has a front lip portion 18' spaced from the leaf 12 so that the portion 19 may be 30 engaged between these parts. The bolt element 18' has a pair of prong portions 18^a which engage around the sides of the catch leaf 12, frictionally engaging these sides and thus maintaining stationary positions. The catch leaf 12 itself is 35 formed with a longitudinal slot 22 extended in from the free end and terminating a slight distance before the inner end thereof. This slot gives resiliency to the catch link, that is, the side portions thereof have a spring to them. The lugs 40 18^a force the side portions of the catch leaf together, and thus the frictional resistance is generated.

The other link 11 has its transverse bar 16 extending through a space beneath the lip 19 45 and between the end wall 20 and the side walls 10^a of the central body. Thus, this link is also pivotally connected with the central body. It should be noted that this link may not be removed as the transverse bar 16 is held against 50 displacement. The other link 11 may be removed over the catch leaf 12 when the latter is in its open position.

The outer catch leaf 13 comprises a bottom wall 13^a from which an outer end hook 24 projects. This hook is adapted to engage over the inner end of the catch leaf 12 when the latter is in the closed position, as clearly shown in Fig. 5. The outer catch leaf 13 also has side walls 25 to reinforce it. These walls 25 termi- 60

nate at the inner end in lugs 26 through which the transverse bar 16 extends. The lugs 26 are substantially in edge alignment with the side walls 10^a of the central body portion. Thus, 5 the outer catch leaf is permanently held in connection with the link 11 and the central body. A finger projection 27 is stamped from the catch leaf 13 by which it may be easily gripped when in the closed position so it may be opened.

10 The links 11 form no part of the invention, but to assist in a better understanding of the invention they will be briefly described. Each link consists of a channel-shaped body portion 11^a in which there is engaged a channel-shaped 15 jaw 11^b. This jaw has a trunnion 11^c on its inner end pivotally mounted on the side walls of the body 11^a. The jaw 11^b is formed with teeth 30 adapted to cooperate with complementary teeth 31 upon the body 11^a by which a 20 bracelet cord may be clamped thereon. Small protuberances 32 are formed on the side walls and jaw 11^b and coact with niches 33 formed in the side walls of the body 11^a, by which the jaw is held closed. The body 11^a has side arms 33. 25 The transverse bar 16 is mounted between the side arms 33.

In Figs. 8 and 9 another embodiment of the invention has been disclosed which is very similar to the previous form, distinguishing merely in 30 the means by which the inner catch leaf 12' is latched in the closed position. According to this form of the invention, lugs 37 are formed on the sides of the catch leaf 12'. These lugs have small protuberances 38 adapted to engage small 35 niches 39 in the side walls 10^a of the central body portion. When the inner catch leaf 12' is moved to the closed position the projections 38 and the niches 39 will hold the leaf in the closed position.

40 While I have illustrated and described the preferred embodiment of my invention, it is to be understood that I do not limit myself to the precise construction herein disclosed and the right is reserved to all changes and modifications coming within the scope of the invention 45 as defined in the appended claims.

Having thus described my invention, what I claim as new, and desire to secure by United States Letters Patent is:—

50 1. A safety catch of the class described, comprising a central body, links with bar portions, an inner catch leaf pivotally mounted on one end of said body and extendible over the bar portion on one of said links, means on the central body and said inner catch leaf for holding the inner catch leaf closed, another one of said links and an outer catch leaf pivotally mounted on the other end of said body, and means for holding the outer catch leaf closed over said 55 inner catch leaf, said means for holding the inner catch leaf closed comprising a bolt element slid- 60 able on the inner catch leaf and engageable with a portion of said central body.

65 2. A safety catch of the class described, comprising a central body, links with bar portions, an inner catch leaf pivotally mounted on one end of said body and extendible over the bar portion on one of said links, means on the central body and said inner catch leaf for holding the inner catch leaf closed, another one of said links 70 and an outer catch leaf pivotally mounted on

the other end of said body, and means for holding the outer catch leaf closed over said inner catch leaf, said means for holding the inner catch leaf closed comprising a bolt element slid- 5 able on the inner catch leaf and engageable with a portion of said central body, said portion comprising a lip formed from an end wall of said central body.

3. A safety catch of the class described, comprising a central body, links with bar portions, 10 an inner catch leaf pivotally mounted on one end of said body and extendible over the bar portion on one of said links, means on the central body and said inner catch leaf for holding the inner catch leaf closed, another one of said links and an outer catch leaf pivotally mounted on the other end of said body, and means for holding the outer catch leaf closed over said inner catch leaf, said means for holding the inner catch leaf closed comprising a bolt element slid- 15 able on the inner catch leaf and engageable with a portion of said central body, said portion comprising a lip formed from an end wall of said central body, said bolt being adapted to engage beneath the lip while the catch leaf 20 extends over the lip.

4. A safety catch of the class described, comprising a central body, links with bar portions, an inner catch leaf pivotally mounted on one end of said body and extendible over the bar 30 portion on one of said links, means on the central body and said inner catch leaf for holding the inner catch leaf closed, another one of said links and an outer catch leaf pivotally mounted on the other end of said body, and means for holding the outer catch leaf closed over said inner catch leaf, said means for holding the inner catch leaf closed comprising a bolt element slid- 35 able on the inner catch leaf and engageable with a portion of said central body, said portion comprising a lip formed from an end wall of said central body, said bolt being adapted to engage beneath the lip while the catch leaf extends over the lip, said bolt having prong portions extending over the sides of the catch leaf for frictionally hold- 40 ing the bolt in adjusted positions.

5. A safety catch of the class described, comprising a central body, links with bar portions, an inner catch leaf pivotally mounted on one end of said body and extendible over the bar portion on one of said links, means on the central body and said inner catch leaf for holding the inner catch leaf closed, another one of said links and an outer catch leaf pivotally mounted on the other end of said body, and means for holding the outer catch leaf closed over said inner catch leaf, said means for holding the inner catch leaf closed comprising a bolt element slid- 50 able on the inner catch leaf and engageable with a portion of said central body, said portion comprising a lip formed from an end wall of said central body, said bolt being adapted to engage beneath the lip while the catch leaf extends over the lip, said bolt having prong portions extend- 55 ing over the sides of the catch leaf for frictionally holding the bolt in adjusted positions, and said catch leaf having a longitudinal slot 60 to give the side portions thereof sufficient springiness to cooperate with said prongs for holding the bolt.

EMANUEL M. ALKIN.
